UNITED STATES PATENT OFFICE.

MELANIE WOLF, OF NEW YORK, N. Y.

SURGICAL BASIN.

1,253,555.

Specification of Letters Patent. Patented Jan. 15, 1918.

Application filed April 14, 1917. Serial No. 162,067.

To all whom it may concern:

Be it known that I, MELANIE WOLF, a citizen of the United States, residing at New York, in the county of New York and State of New York, have invented new and useful Improvements in Surgical Basins, of which the following is a specification.

The present invention pertains to basins and expectorating trays which may be used 10 independently or in connection with the ordinary dental or medical cuspidor or in connection with an ordinary waste receptacle or drain pipe, or a receptacle or drain pipe on a medical examining or operating 15 table or the like.

Any person sitting in a dental or medical chair, especially a stout or feeble person, will have noticed how inconvenient, embarrassing and sometimes almost impossible 20 it is to bend sidewise or forward and expectorate into the pre-arranged medical or dental cuspidor used at present.

The same is also particularly true of persons just recovering from the effects of an 25 anesthetic or similar effects, who are unable to move freely and are compelled to maintain the position they happen to be in; therefore it will be of great advantage to be able to adapt the position of the expectorating tray or basin to the ever-varying 30 needs of the respective patient.

My device may also be used to great advantage when making operations on the mouth, nose, face, eyes, neck or other operations 35 on any part of the body, in which latter case it may be used as a basin to collect various material, also when syringing wounds in the mouth, nose, face, or any other part of the body, all material and 40 liquid is thus easily collected and carried away, saving the patient from inconvenient posture and his clothing from being wetted or soiled.

For dental purposes my device is adapted 45 to be very useful when syringing the mouth for cleaning purposes or when syringing it while taking wax, modeling compound or other impressions, when making tooth extractions or other operations, when syringing 50 wounds, affections or lesions in the mouth, antrum, nose, face, head, neck or the like, or teeth or cavities of teeth, also for persons just recovering from the effects of an anesthetic or faint—for all these cases 55 the surgical basin will prove of great ad-

vantage, as it is adjusted to a position where needed, for instance, closely beneath the patient's lips if the basin is used as spittoon, instead of requiring him to adapt himself to the position of the spittoon, which latter 60 in a majority of cases is placed at an inconvenient distance from the patient's lips, requiring change of position on the part of the patient or person using it.

My device is also greatly useful for young 65 children who usually touch the dental or medical cuspidor they use with their hands, and frequently touch or almost touch it with their mouths when expectorating, thus exposing themselves to contagion if diseased 70 matter adheres to the ordinary cuspidor. When using my device, a clean expectorating basin could be easily slipped in position, if desired, the expectorating basin adjusted 75 to the height and requirements of the respective patient, and the entire device be made ready for use in a few moments.

Another great advantage of the surgical basin described in the following, is the fact that it can be easily detached, cleaned and 80 sterilized, or made of a suitable material as, for instance, waxed paper or papier mâché, intended to be destroyed with the contents after being used once, as in cases 85 of syphilis or other communicable disease.

In the preferred arrangement which is illustrated in the accompanying drawings, similar figures denote corresponding parts.

Figures I and II are general views of my device, the adjustable basin being attached 90 in two different manners; Fig. III shows in detail the method of attaching the gooseneck carrying the basin to the head-rest of a dental chair; Fig. IV shows a method of suspending the adjustable basin so that it can 95 be easily disengaged, it also shows one method of attaching the lower end of the drain tube in the bowl of the dental or medical cuspidor now in use; Fig. V shows in detail another method of attaching the 100 lower end of the drain tube in the bowl of the cuspidor; Fig. VI shows the method of attaching my device to an adjustable head-rest fastened to the back of an ordinary chair; Fig. VII shows the adjustable basin 105 having its drain tube temporarily closed.

Figs. I and II represent a general view of my invention, the device being attached to a dental chair.

1 in Fig. I represents the expectorating 110

tray or basin, kidney-shaped, so that one side of the basin accommodates itself to the shape of the patient's neck, in order to enable him to expectorate into the basin 5 without changing the position of the head, and without getting his clothing wetted or soiled. The basin is provided with an outlet 2 to which the flexible drain tube 3 is either permanently or removably attached.

10 Outlet 2 may be omitted, putting the drain tube 3 out of commission, if desired.

15 4 is a flexible gooseneck, adapted to maintain temporarily its position to which it is bent or adjusted, supporting basin 1 which is removably attached to it, and fastened to the upright 5 of the headrest of the dental chair by means of the clamp 7 which may be as shown in detail in Fig. III. From the basin 1 a flexible tube 3 leads to the bowl 20 8 of the dental cuspidor, which tube is adapted to drain off expectorated or other waste matter from the basin 1 into the ordinary dental cuspidor.

25 The supporting device 9 of the gooseneck 4 holding the basin 1 in position, may be a clamp, as shown in Fig. I, or readily detachable, as shown in Fig. IV, 9'.

30 The gooseneck 4 of Fig. I may be done away with if the drain tube 2, Fig. I is is made of a construction so as to combine the principle of the gooseneck with the flexible drain tube, as shown in 10, Fig. II, so that the drain tube 10 carrying the basin 1 maintains any position to which it may be 35 adjusted, and carries off any waste material from the basin 1 to the bowl of the ordinary dental or medical cuspidor to which it is, preferably removably, attached. This tube 10 may be supported by some convenient 40 support, as 11, to steady the same if considered necessary.

45 The suspension device, shown in Fig. IV, 9', consists of a curved strip of metal which is attached to gooseneck 4, having a square opening 12 on one end into which is slipped a projection 13 of basin 1, and a slot 14 on the other end of said strip into which is slipped projection 15 of basin 1.

50 I am aware of the fact that the gooseneck arm can be replaced by any other adjustable arm or any support or stand, and that said gooseneck arm or other suitable support can be attached to any other part of the chair, or to any part of an invalid chair, bed, 55 table or spittoon or other convenient object.

56 The basin 1 can also be supported from the floor, walls or ceiling, the main purpose being that it is capable of being adapted 60 to be adjusted and supported near patient's lips or other part of the body where needed, without requiring the patient or person using it to change his position.

65 Fig. IV is a sieve-like arrangement or trap, which may be of various shape and

removable, situated at the junction of basin 1 with the drain tube 3, designed to prevent clogging of drain tube 3 by any solid matter, as vomited matter, blood clot, plaster, cotton or other material.

70 17 is a hollow plug or metal ferrule forming the lower part of drain tube 3, designed to fit into the short tube or guide 18 which is adjusted to the inner part of the bowl of the dental or medical cuspidor by means of 75 a suitable support 19, as shown in Fig. IV, or to a metal rim 20, Fig. V, which is designed to fit over the rim of the bowl 8 of the dental or medical cuspidor. 17 has a collar 28 which prevents it from slipping 80 too far into guide 18.

It is obvious that the lower end of the drain tube 3 of the adjustable basin can also be attached to any other part of the cuspidor, waste receptacle or any waste or drain 85 pipe, or it may rest detached in any waste receptacle, spittoon or drain pipe.

The lower end of the drain tube 3 can also be arranged in a manner so that the outlet of the same is held in position by a 90 suitable attachment within the bowl of the ordinary dental or medical cuspidor, just above the latter's outlet or trap.

95 22, Figs. I, II and IV is a set-screw, designed to clamp or fasten basin 1 to drain tube 3. 23, Fig. I is a suitable support attached to the dental or medical cuspidor and designed to support basin 1 when not in use. This support is shown as a fork-like arrangement but may be of any suitable 100 shape and may be attached to any desired object, or to the floor, wall or the like.

105 It will be noted that by means of this arrangement the basin or bowl of my device, which basin may be of various shape to suit the particular case on hand, can be easily adjusted to the respective position or needs of the patient or person using it, without changing his position, or it may be used for syringing or similar purposes, for 110 medical operations or the like, the expectorated or other matter draining off through tube 3 into the bowl 8 of the dental or medical cuspidor or other receptacle or drain pipe, any matter that is apt to clog the tube 115 3 is held back by the trap 16, and the basin can be easily detached and exchanged by lifting it from support 9' for cleaning or other purposes, and by loosening set-screw 22. If desired, a water flush or flushing device can be used in the basin.

120 After cleansing the basin may be placed out of the way on support 23 for future use. Also the drain tube may be readily and easily detached from guide 18 for 125 cleansing or other purposes by drawing out plug 17 whenever desired.

126 The gooseneck 4 may also be designed to be attached to any detachable head-rest 24, as shown in Fig. VI, which is used on medi- 130

cal or ordinary chairs, or it may be attached to any other part of a chair, and the rest of the device may in this case be essentially the same as described above. With regard to 5 the lower end of drain tube 3, the same may be permanently closed at the lower end or merely temporarily, by means of screw cap 26, as shown in Fig. VII. The basin shown in Fig. VII has a projection on either side 10 designed to engage part 9', and thus is capable of being easily slipped in position, when needed.

If this device is used, I prefer to have the basin and tubing made of any very light 15 material as, for instance, aluminum, celluloid, papier mâché or waxed paper, or thin flexible rubber. If the material is flexible as, for instance, when soft rubber is used, the lower end of tube 3 can be easily closed 20 water-tight by means of a suitable clamp 25 or any other suitable device, or it can be rolled up, kinked or the like. For cleaning purposes the entire basin and tubing could easily be inverted after detaching the basin 25 and removing the clamp.

The drain tube 3 can be permanently closed, and this arrangement would be suitable if it is intended to destroy the basin, tube and contents as soon as the former is 30 used, as in cases of contagious or communicable diseases. In this case the device could be conveniently manufactured of waxed paper or papier mâché on account of its adaptability and nominal cost of manufac- 35 ture.

I do not wish to restrict myself to the particular construction and arrangement shown, but—

What I claim and desire to secure by Letters Patent is:

1. An attachment for dental or medical 40 cuspidors, consisting of an auxiliary spittoon or medical basin provided with an outlet, a flexible drain-tube connected to said 45 outlet, the dental or medical cuspidor provided with an adjustable rim which provides

an opening, the lower end of the drain-tube being adjusted or connected to said opening, whereby the auxiliary basin may be adjusted in any position desired.

2. An attachment for dental or medical cuspidors, consisting of an auxiliary spittoon or medical basin provided with an outlet, a flexible goose-neck drain-tube connected to the outlet of said auxiliary spittoon or basin and supporting the same, the dental or medical cuspidor provided with an adjustable rim which provides an opening, the lower end of the drain-tube being adjusted or connected to said opening, whereby the auxiliary spittoon or basin may be adjusted in any position desired.

3. In combination with a dental or medical cuspidor and chair, an auxiliary spittoon or medical basin, with means for fastening the same to the chair, the auxiliary spittoon or basin provided with an outlet, a flexible drain-tube connected to the outlet of said auxiliary spittoon or basin, the dental or medical cuspidor provided with an adjustable rim which provides an opening, the lower end of the drain-tube being adjusted or connected to said opening, whereby the auxiliary spittoon or basin may be adjusted in any position desired.

4. An attachment for dental or medical cuspidors, consisting of an auxiliary spittoon or medical basin provided with an outlet, a flexible drain-tube connected to said outlet, the dental or medical cuspidor provided with an adjustable arm which is provided with an opening or attachment for engaging the lower end of the drain-tube, said lower end of the drain-tube being adjusted to or connected to said opening or attachment, whereby the auxiliary spittoon or basin may be adjusted in any position desired.

MELANIE WOLF.
